A. H. WICKS

DUST CAP

Filed Sept. 26, 1923

Inventor
Arthur H. Wicks
By May K. Zabel Atty.

UNITED STATES PATENT OFFICE.

ARTHUR H. WICKS, OF WOODSTOCK, ILLINOIS.

DUST CAP.

Application filed September 26, 1923. Serial No. 664,895.

To all whom it may concern:

Be it known that I, ARTHUR H. Wicks, a citizen of the United States, residing at Woodstock, in the county of McHenry and State of Illinois, have invented a certain new and useful Improvement in Dust Caps, of which the following is a full, clear, concise, and exact description, reference being had to the accompanying drawings, forming a part of this specification.

My invention relates to dust caps for tire valves, and more particularly to a quickly detachable dust cap.

It is a purpose of my invention to provide a simple, quickly detachable dust cap which can be very cheaply and simply made and which is firmly held in frictional clamping engagement with a valve stem when in position due to the resiliency thereof.

My improved dust cap is made of sheet metal and is not provided with any projections, threads or other device to engage with the threads on the valve stem but, instead, is made of a cross sectional shape similar to that of a coil spring having a little over one turn. In other words, the side wall portion of the cap is closed by overlapping the edges of the material from which the cap is made, thus making a lapped joint, the material not being secured together in any way except at the closed end of the cap. Due to this construction the edge portions of the material where the lapped joint occurs can move over each other and act substantially as a coil clock spring would act.

Moreover, my improved cap is preferably tapered so as to be considerably smaller at the open end thereof than at the closed end. The open end of the cap is preferably smaller than the threaded portion of the valve stem and, accordingly, the cap will grip the valve stem threads with a spring action.

Other objects and advantages of the invention will appear as the description of the accompanying drawings proceeds. However, I desire to have it distinctly understood that I do not intend to limit myself to the exact details shown or described but that I intend to include as part of my invention all such obvious changes and modifications of parts as would occur to a person skilled in this art and as would fall within the scope of the claims.

In the drawings:

Fig. 1 is a fragmentary view of a wheel felly with a valve stem projecting there-

from, showing my improved dust cap in longitudinal section in position thereon.

Fig. 2 is a side elevation of my improved dust cap, showing the position which it assumes when forced on the threaded valve stem in dotted lines; and

Fig. 3 is an enlarged sectional view taken on the line 3-3 of Fig. 1, the valve mechanism contained within the valve stem being omitted.

Referring in detail to the drawings, in Fig. 1 is shown a fragment of a wheel felly 10 with a valve stem 11 projecting therefrom, said valve stem being threaded at 12 70 as is customary and having the flattened portions 13 as is well known. The valve mechanism is provided with the ordinary valve cap 14.

Mounted on said valve stem is my improved dust cap comprising a body portion 15 and a closed end portion 16. The body portion 15, as will be clear from Fig. 3, is made of a sheet of material having overlapping portions 17 and 18 at the edges 80 thereof that extend longitudinally of the cap. Thus, a lapped joint is provided extending longitudinally of the cap with the overlapping portions 17 and 18 thereof free to move over each other. As the material from which the cap is made should be resilient sheet metal, it is evident from Fig. 3 that the cap will in effect be a coil spring having slightly more than a single coil of the width corresponding to the length of the cap from the 90 open end thereof to the portion 19 thereof where the side wall portion joins the closed end wall portion of the cap.

The open end of the dust cap is beaded over at 20, as indicated in Figs. 1 and 2, 95 said beading being beveled off as indicated at 21 so as to permit sliding of the beads over each other in a similar manner to the overlapping portions 17 and 18.

Preferably, the dust cap is tapered, as indicated in Fig. 2, being of smaller diameter at the lower end 22 thereof than at the portion 19 thereof. Said open end portion 22 of the dust cap when in the position shown in full lines in Fig. 2, which is the normal 100 position of the material of said cap, is of considerably smaller diameter than the threaded portion of the valve stem. Accordingly, when the dust cap is forced on the valve stem the side wall portion thereof 110 will assume the position shown in dotted lines in Fig. 2 and the cap will grip the

valve stem with a spring action. The end of the side wall portion adjacent the closed end of the cap is preferably of substantially the same size as the valve stem as the said end thereof will be substantially of the same diameter due to the closed end being adjacent thereto. However, from the portion 19 where the closed end and the side wall portion join to the open end of the 10 cap, the cap will have a gradually decreasing diameter and a gradually increasing spring action.

Having thus described my invention, what I desire to claim and secure by United States 15 Letters Patent is:

1. A dust cap having a body portion of spring metal having overlapping edges extending lengthwise of said cap, said edges always overlapping to close the side wall 20 of said cap and being slidable over each other, whereby the diameter of said cap may be varied.

2. A dust cap having a body portion of sheet metal having overlapping free edges 25 extending lengthwise of said cap, said body portion being distortable so that said edges slide over each other, whereby the diameter of said cap may be varied, said cap decreas-

ing in normal diameter toward the open end thereof, and said edges overlapping at all 30 times to maintain a dust tight joint at said free edges.

3. A dust cap having a body portion having overlapping free edges extending lengthwise of said cap, the normal amount of overlap of said edges increasing from adjacent the closed end of said cap toward the open end thereof the amount of overlap of said edges being such that the same overlap at all 35 times to form a dust tight cap.

4. A dust cap having a body portion of resilient material provided with a closed end and a side wall portion having overlapping free edges, said overlapping edges extending from said closed end to the open end 40 of said cap, the overlap thereof increasing toward said open end to provide a body portion normally tapering toward the open end of said cap the amount of overlap of said edges being such that the same overlap 45 at all times to form a dust tight cap.

In witness whereof, I hereunto subscribe my name this 15th day of September, A. D., 1923.

ARTHUR H. WICKS.
